UNITED STATES PATENT OFFICE

2,675,763

HYDRAULIC RADIAL ENGINE

Theodor Müller, Winterthur, Switzerland, assignor to Schweizerische Lokomotiv- und Maschinenfabrik, Winterthur, Switzerland

Application September 14, 1948, Serial No. 49,139

Claims priority, application Switzerland September 22, 1947

5 Claims. (Cl. 103—161)

1

My present invention relates to improvements in expansible chamber type motors or pumps comprising a moving radiating cylinder block, reciprocating pistons and a rotating outside abutment; and in particular to an improved construction of the enlarged piston heads and of the correspondingly extended cylinder walls of such engines in which the piston end remote from the cylinder working space abuts slidably against a flat face of the abutment, and in which a pressure chamber is recessed from the said piston end, which chamber is supplied with pressure fluid from the appurtenant cylinder space in order to substantially counter-balance the pressure exerted by the operating fluid on the inner piston face.

The principal object of my present invention is to bring the piston head closer to the abutment face and to reduce the lateral pressures against the piston guideway, which result from the friction arising on the abutment face. According to my present invention, therefore, the enlarged piston head is guided in a guideway which is rigidly secured to the cylinder and has a greater diameter than the latter. The free end of the said guideway extends into close proximity of the piston abutment face at the inner dead-center position of the piston. The enlarged piston head is made of such length as to be still enclosed by the said guideway for a short distance also in the outer dead-center position of the piston.

In the drawing, Fig. 1 is a longitudinal sectional view of a piston of known type, and Fig. 2 is a view on the piston head, partly drawn in section, in the direction of the arrow A in Fig. 1.

Fig. 3 shows an engine of the type indicated in section on the line III—III of Fig. 4,

Fig. 4 a side view thereof in section on the line IV—IV of Fig. 3,

Fig. 5 the piston head in larger scale, and

Fig. 6 a plan view of the piston head of Fig. 5, in direction of the arrow B in Fig. 5.

Fig. 7 is a fragmentary sectional view similar to Fig. 5 showing a modified piston.

In known engines of the type indicated, of which a piston form is shown in Figs. 1 and 2 of the accompanying drawing, that face of the piston head 15 which serves as abutment face, is larger than the cross-section of the appurtenant working cylinder 19. The enlarged head 15 is of disadvantage in that the cylinder wall guiding the piston cannot be brought closer down to the abutment face 11 than is permitted by the height of said head 15, as shown by dash lines at 35 in Fig. 1, so that frictional forces arising on

5 said face 11 give origin to detrimental lateral pressures on the guideways of the piston in the cylinder. A guideway of maximum length also is desirable, however, with respect to eventually 10 present stay ledges 27 (Figs. 1, 2) which serve for preventing too great a detachment of the piston head from the said face 11. Even when two such ledges 27 are provided for, first one thereof will abut—in case of slight irregularities—against the 15 rear side of the head 15 and give rise to an eccentric pull which also may cause very inconvenient lateral pressures on the piston, which pressures may lead to a seizing of the piston.

According to Figs. 3 and 4, the cylinder block 3 comprising three radially disposed cylinders is 15 mounted rotatably on the control stud 2 which is rigidly secured to the casing 1. In the latter, further, the abutment 5 is mounted rotatably at 6 and 7 and eccentrically to the axis of stud 2, and is so coupled to the cylinder block 3, by means 20 of a follower 9 in form of a cross-loop or universal coupling, that the cylinder block 3 and the abutment 5 always rotate at the same number of revolutions. On the inside wall of abutment 5, 25 which may be driven through the stub shaft 10 when the engine shall operate as a pump, three flat faces 11 are provided, against which the heads of the pistons 12, 13 abut.

The piston 12 through its slide shoe or piston head 15, abuts directly against the appurtenant supporting face 11. The pistons 13, however, of which only one is fully shown, abut against their faces 11 through the intermediary of an adjustable spherical segment 28.

35 Bores 4 are provided in the said fixed control stud 2 and serve for supplying and delivering the operating fluid, e. g. in the sense of the arrows shown in Fig. 4. The cylinders situated above the horizontal median plane of the stud 2, 40 communicate with the upper bore 4, and the cylinders situated below the said plane communicate with the lower bore 4. The web 8 separates the suction and the pressure space of the engine from each other.

45 A shallow pressure chamber 16 defined by the narrow annular face 23 is recessed from the flat end face of segment 28 of the piston 13 (Fig. 5), which face abuts against the supporting face 11 of rotor 5. The said chamber is supplied with pressure fluid from the cylinder interior 19 through the bores 20 and 30, thus counter-balancing the pressures exerted by the operating fluid onto the inner piston face 22. The spherical segment 28 permits slight deviations of the longitudinal axis of the piston from a line standing at

right angles to the abutment or supporting face 11.

The enlarged piston head 32, in which the spherical face of the segment 28 is mounted, is guided, in accord with my present invention, by means of two diametrically opposite guideways 33 rigidly secured to the cylinder 3. The said ways 33, at the inner dead-centre position of the piston 13, with their free ends 35 extend very closely to the said face 11, as shown by the dash lines in Fig. 5. Further, the enlarged piston head 32 is of such length that, also at the outer dead-centre position of the piston, the latter will not leave the guideways 33 and will still be engaged thereby over a short distance, as shown in Fig. 5.

In order to prevent the piston from being raised too much from the abutment or supporting face 11, retaining ledges 27 are provided on the abutment 5 and are engaged in a groove 34 of the piston head 32. The guideway 33 is interrupted on the sides where the ledges 27 are engaged by the piston head, so that the guideway engages the piston head only between the ledges 27 by means of two lugs. In the modification shown in Fig. 7, the piston head is constructed in the same manner as in Fig. 5, but instead of with a continuous circular groove 34, the piston end portion is provided with two opposite peripheral slots 36 in engagement with the two diametrically opposite ledges 27. The piston is thus prevented from being unduly raised off the abutment face 11, and from rotating freely about its longitudinal axis.

A retaining ledge 27 also may be provided on one side only of the piston, in which case the guideway 33 may be cut back on this side only and be kept complete on the opposite side.

The invention also may be applied to engines which are operated by means of a gas as operating or pressure fluid respectively.

What I claim as new and desire to secure by Letters Patent is:

1. A fluid operated radial piston engine comprising a casing, a rotor movable in said casing, a cylinder block having radial cylinders eccentrically mounted in said rotor, a piston operating in each radial cylinder, each piston having a body portion slidably engaged within the cylinder and an enlarged end portion, said rotor being provided with flat abutment faces in sliding engagement with the enlarged piston ends, each piston end having a pressure chamber recessed therein, the piston being provided with a longitudinal bore connecting said pressure chamber with the cylinder space to supply pressure fluid from the cylinder space to the pressure chamber, extensions on said cylinders forming guideways for the enlarged piston end portions, said guideways being of such radial length as to arrive in close proximity of said piston end supporting abutment faces at inner dead center position of the piston, and the enlarged piston end portions being of such length as to remain engaged by said guideways at outer dead center position of the piston, each piston having the enlarged end portion provided with a peripheral recess, and retaining means carried by the rotor and engaging said peripheral recess in the piston end portion to prevent the piston

from being unduly raised off said abutment face.

2. A fluid operated radial piston engine as claimed in claim 1, wherein said piston retaining means is formed by two diametrically opposite ledges carried by the rotor and penetrating between said guideways to engage a circumferential groove provided in said enlarged piston end portion.

3. A fluid operated radial piston engine as claimed in claim 1, wherein said piston retaining means is formed by two diametrically opposite ledges carried by the rotor and penetrating between said guideways to engage two opposite peripheral slots in said enlarged piston end portion.

4. A fluid operated radial piston engine as claimed in claim 1, wherein said enlarged piston end portion is provided with a recess having a spherical bottom, a spherically curved segment being engaged in said recess and having a flat end face provided with said pressure chamber and slidably engaging said flat abutment face on the rotor.

5. A fluid operated pump or motor comprising a cylinder block having radial cylinders, a piston operating in each cylinder each piston having a body portion slidably engaged within the cylinder and an enlarged end portion, a thrust member surrounding said cylinder block, said thrust member being provided with flat abutment faces in sliding engagement with the enlarged piston ends, each piston end having a pressure chamber recessed therein, the piston being provided with a longitudinal bore connecting said pressure chamber with the cylinder space to supply pressure fluid from the cylinder space to the pressure chamber, extensions on said cylinders forming guideways for the enlarged piston end portions, said guideways being of such radial length as to arrive in close proximity of said piston end supporting abutment faces at inner dead center position of the piston, and the enlarged piston end portions being of such length as to remain engaged by said guideways at outer dead center position of the piston, each piston having the enlarged end portion provided with a peripheral recess, and retaining means carried by the thrust member and engaging said peripheral recess in the piston end portion to prevent the piston from being unduly raised off said abutment face.
